Primary Examiner — Cynthia M Chin(74) *Attorney, Agent, or Firm* — Perry Hoffman(57) **CLAIM**

The ornamental design for a toy gun, as shown and described.

DESCRIPTION

FIG. 1 is a reduced perspective view of the toy gun of the instant invention;

FIG. 2 is a front elevation view thereof;

FIG. 3 is a rear elevation view thereof;

FIG. 4 is a top view thereof;

FIG. 5 is a bottom view thereof;

FIG. 6 is a right side elevational view thereof; and,

FIG. 7 is a left side elevational view thereof.

The broken lines shown are included for the purpose of illustrating the unclaimed portions of the article that form no part of the claimed design.
